UNITED STATES PATENT OFFICE.

JAMES A. VALLENTINE, OF NEW YORK, N. Y.

FAUCET ATTACHMENT AND BUSH.

SPECIFICATION forming part of Letters Patent No. 224,057, dated February 3, 1880.

Application filed April 25, 1879.

To all whom it may concern:

Be it known that I, JAMES A. VALLENTINE, of New York city, New York, have invented an Improved Faucet Attachment and Bush, 5 of which the following is a specification.

The object of my invention is to improve the construction of faucet attachments and bushes to be used in barrels or casks containing liquors of any kind; and the invention consists in the 10 construction and arrangement of parts, as will be more fully described hereinafter, reference being had to the accompanying drawings and the letters of reference marked thereon.

Like letters refer to like parts in the figures.

15 In the drawings, Figure 1 is a longitudinal vertical section of the faucet attachment and bush. Fig. 2 is a side view of the key for operating the same. Fig. 3 is a section and front view of the plug for closing the valve when 20 the faucet is removed. Fig. 4 is a longitudinal section and end view of the valve and bush. Fig. 5 is a vertical section of the valve and faucet detached from each other.

In the drawings, A represents a barrel-bush, 25 provided with a screw, E, for screwing it into the barrel; or it may be made smooth on its outer surface for driving it into the barrel. This bush is provided with a screw-thread on its inner end, into which the valve D fits.

30 The valve has a hole, d, in it, which forms a continuous channel, through which the liquors pass when the faucet is opened. The inner end of the valve is reduced in size, and over the reduced end the faucet K fits, and by abutting 35 against the end of the valve a perfectly-tight joint is formed, so that there can be no leakage, and the two thus form a continuous channel.

The exterior screw, C, fits the interior screw 40 at the rear end of the bush, and forms a close plug when turned into position in opening the valve, as shown in Fig. 1.

When it is desired to remove the faucet a screw-plug, a, is inserted into the outer threaded 45 end of the bush, and said bush is operated by a key, G, having its end H tapered, which fits into the recesses I, I, Fig. 4, and can be thus secured or removed.

The bush A is recessed, as shown at b, so as to reduce the length of screw-thread, although this might extend the outer end. 50

The operation is as follows: The plug A, with the valve D, is first screwed or driven into the barrel, and the faucet is then screwed onto the reduced end of the valve and into the 55 inside part of the bush, as shown in Fig. 1. The valve D is then forced into the barrel by the faucet, which forms a tight joint at d', and when in this position a communication is 60 opened with the contents of the barrel, and a continuous, channel is thus formed with the faucet.

The advantages of my device are that the parts can be made of any desired material and of any size required, they are not liable to get 65 out of order, any of the parts can be easily replaced when worn out or repaired when broken, and the device can be furnished at a very small cost.

Having thus described my invention, what 70 I claim, and desire to secure by Letters Patent, is—

1. The combination of the bush A with the valve D and faucet K, provided with an interior and exterior thread for attachment to 75 the valve D and bush A, when arranged substantially as and for the purpose described.

2. The combination of the bush A, provided with exterior and interior threads, with the valve D, having a reduced threaded end, upon 80 which the inner threaded end of the faucet K fits for operating the valve, as shown and described.

3. The combination of the faucet K, provided with interior and exterior threads, with 85 the valve D, having a reduced threaded end for attachment to the faucet, and the enlarged threaded end for securing it to the bush A, all constructed and arranged substantially as shown and specified.

JAMES A. VALLENTINE.
